UNITED STATES PATENT OFFICE.

GEORGE M. COCKE AND EMIL SEIDEL, OF MILWAUKEE, WISCONSIN.

DESIGN FOR A RADIATOR.

SPECIFICATION forming part of Design No. 28,199, dated January 18, 1898.

Application filed December 15, 1897. Serial No. 662,081. Term of patent 7 years.

To all whom it may concern:

Be it known that we, GEORGE M. COCKE and EMIL SEIDEL, both of Milwaukee, in the county of Milwaukee and State of Wisconsin, 5 have invented and produced a new and original Design for Radiators; and we do hereby declare that the following is a full, clear, and exact description thereof, reference being had to the accompanying drawing, which forms a part of this specification.

The drawing shows in side elevation a radiator-section embodying our design.

As shown in the drawing, the leading or material distinguishing features of our design 15 are the contour of the radiator-section and the surface ornamentation, the outline of the radiator-section conforming to the ornamentation and with it producing the complete design. The radiator-section comprises three 20 vertical parts and three cross connections having rounded surfaces and enlarged or swelled and rounded ends, the two outer vertical parts being extended at their lower ends into legs. The middle upright part has at its 25 upper end a foliated rosette 1, from the lower part of which a leaf-like scroll or appendage 2 extends in low relief down over the surface of said middle upright part. This rosette is 30 partially surrounded above and on the sides by a leaf-like border 3, consisting of radially-arranged conventional leaves infolded at their outer edges and coinciding with the outline of the radiator-section at the top. The two 35 outer vertical parts have at their upper ends volute ornaments 4, with scroll or leaf-like appendages 5 and 6 springing therefrom and extending down upon said outer parts, the outline of the volutes 4 and the scrolls 5 forming a portion of the outline of the upper part 40 of the radiator-section. At the intersection

of the middle upright and cross parts of the radiator-section is a three-lobed boss-shaped ornament 7, from which scroll and leaf-like appendages 8 and 9 and conchoidal or shell-shaped ornaments 10 10 extend in opposite 45 directions upon the middle vertical and cross parts of the radiator-section. Scrolls or leaf-like appendages 11 and 12, interlaced with said conchoidal ornaments 10, project upwardly and downwardly therefrom upon the 50 outer vertical parts of the radiator-section. At the lower end of the middle vertical part is a rosette 13, having a plain center, and on each side of this rosette is a foliated volute 14, the outer side of which coincides with a 55 portion of the outline of the radiator-section. The lower end of the middle vertical part of the section conforms in outline with the lower side of the rosette 13. Leaf-like or scroll appendages 15 15, springing from the volutes 14, 60 extend upwardly upon the outer vertical parts, and leaf-like appendages 16 extend upwardly from the rosette 13 upon the middle vertical part of the radiator-section and have their stems interlaced with curved bands 65 above and approximately concentric with the rosette 13.

Having thus described our invention, what we claim as new, and desire to secure by Letters Patent, is—

The design for a radiator substantially as shown and described.

In testimony that we claim the foregoing as our own we affix our signatures in presence of two witnesses.

GEORGE M. COCKE.
EMIL SEIDEL.
